UNITED STATES PATENT OFFICE.

PAUL S. BUTTERWORTH, OF RICHMOND, VIRGINIA.

DESIGN FOR A PENDANT OR WATCH-CHARM.

No. 38,652.

Specification for Design.

Patented July 9, 1907.

Application filed May 4, 1907. Serial No. 371,936. Term of patent 3½ years.

To whom it may concern:

Be it known that I, PAUL S. BUTTERWORTH, a citizen of the United States, residing at Richmond, in the county of Henrico and State of Virginia, have invented a new, original, and ornamental Design for Pendant or Watch-Charm, of which the following is a specification, reference being had to the accompanying drawing, forming part thereof.

The figure is a side view of a pendant or watch charm showing my new design.

I claim:

The ornamental design for a pendant or watch charm as shown.

PAUL S. BUTTERWORTH.
